REMOVABLE DENTURE

Robert J. Maniola, deceased, late of Chicago, Ill.,
by James J. Maniola, administrator, Chicago,
Ill., assignor to James J. Maniola, Chicago, Ill.

Application September 16, 1947, Serial No. 774,335

14 Claims. (Cl. 32—6)

1

This invention relates to improvements in dentures, and particularly to that class of dentures intended to be applied more or less permanently to an edentulous space, either in an anterior or posterior position in the mouth, and either to the upper or lower set of teeth.

This invention is, in certain respects, an improvement over that disclosed in the applicant's application for removable dentures, Serial No. 744,205, filed April 26, 1947.

One object of the invention is to provide improved dentures which utilize the natural undercutts of the abutment teeth, whether anteriorly or posteriorly located, for retaining the denture in proper position within the edentulous space.

Another object of the invention is to provide a denture which is adapted to seat in an edentulous anterior or posterior area defined by natural undercut mesial and distal surfaces of the abutment teeth and which avoids the formation of objectionable food traps or cavities by closing all the interproximal spaces spanned by the denture.

An additional object of the invention is to provide a denture of at least three cooperating parts which are separately insertable into the edentulous area or space for which they are made and which, when secured in said area or space, closely contact the mesial and distal surfaces of the abutment teeth for retention in position against vertical and lateral displacement.

A still further object is the provision of a denture of three cooperating parts which are separately insertable into the edentulous space in a predetermined consecutive order, the last-insertable part being an artificial tooth securable to one of the previously-insertable parts and being effective to maintain all three parts firmly in the space for which they are made.

Other objects of the invention relate to various features of construction which will be apparent from a consideration of the following specification and accompanying drawings, wherein

Figure 1 is a broken lower plan view of a set of upper teeth;

Fig. 2 is an elevation of the teeth of Fig. 1 as viewed from a position indicated by line 2—2 of Fig. 1 and showing an artificial denture in place;

Fig. 3 is a view similar to Fig. 2 but illustrating the last-insertable part comprising the keying tooth in position in broken lines and in a removed position in full lines;

Fig. 4 is a view also similar to Fig. 2 but showing only the first-insertable section of the denture in position in the edentulous space and the second-insertable section in a removed position;

2

Fig. 5 is a sectional view taken on line 5—5 of Figs. 1 and 2;

Fig. 6 is a broken, enlarged, partially sectioned, buccal view of the denture in longitudinal section and showing the relation thereof to the two abutment teeth;

Fig. 7 is a perspective view of the three parts of which the denture is formed, the parts as shown being separated and inverted;

10 Fig. 8 is a view similar to Fig. 6 but illustrating an embodiment in which only one of the abutment teeth is mesially or distally undercut;

Fig. 9 is a broken lower plan view of a set of upper teeth illustrating another embodiment of 15 the present invention and showing how the invention may be applied to an anterior position in the mouth, that is to replace front teeth;

Fig. 10 is an elevation of the teeth of Fig. 9 as viewed from a position indicated by the line 20 10—10 of Fig. 9 and showing the first- and second-insertable parts in assembled position within the edentulous space and the third-insertable part comprising the key-tooth illustrated in assembled position in broken lines and in removed 25 position in full lines; Fig. 10 corresponds to the view shown in Fig. 3 for the first disclosed embodiment;

Fig. 11 is a view similar to Fig. 10 but illustrating the first-insertable part in assembled position 30 and the second-insertable part in removed position;

Fig. 12 is a sectional view taken on line 12—12 of Fig. 9;

Fig. 13 is a sectional view taken on line 13—13 35 of Fig. 11;

Fig. 14 is a sectional view taken along the line 14—14 of Fig. 9;

Fig. 15 is a fragmentary, enlarged, partially sectioned lingual view of the denture as seen 40 along the line 15—15 of Fig. 9; and

Fig. 16 is a perspective view of the three parts of which the denture is formed, the parts as shown being separated and inverted.

The embodiment shown in Figs. 1 through 8 45 will first be described; then the embodiment shown in Figs. 9 through 16 will be described.

In the drawings, Figs. 1 through 8, a set of natural upper teeth are shown, two posterior teeth having been replaced by a denture that is 50 illustrative of one embodiment of the present invention. The two natural teeth that have been removed are the second right bi-cuspid and the first molar. Hence, the abutment teeth for the edentulous area caused by the removal of the two natural teeth are the first right bi-cuspid 10 and 55

the second right molar 11. As indicated, particularly in Fig. 6, the distal surface of tooth 10 and the mesial surface of tooth 11 are undercut surfaces, that is, each converges generally toward the root tip of the respective tooth. These surfaces are usually naturally undercut in this manner due to the characteristics of teeth to be broader at the occlusal or biting surface than at the root; where desired, this undercut can be suitably modified artificially, by grinding. These undercut surfaces have been a source of trouble in making conventional removable partial dentures that avoid the formation of food traps, but such undercut surfaces are utilized in the present improvements for retention of the dentures in place and without the use of bars and clips of the types that heretofore commonly have been used.

The denture illustrated in Figs. 1 to 7 comprises three coacting parts, namely, sections A and B which are insertable in the edentulous area in the order named and the keying-tooth C which is securable to A, as by cementing, to hold the assembled denture securely in place. Fig. 7 illustrates the parts A, B, and C as viewed from the left in Fig. 1, that is from the buccal side, and also shows the parts in inverted relation, Fig. 1 being a view of the upper set of teeth. The section A is a casting of metal or a molding of appropriate plastics material and comprises a surface 12 saddle-shaped in accordance with the gum surface or ridge portion over which it is to be worn, as indicated in Fig. 5. The body portion 13 of section A has formed thereon a vertical portion or pillar 15 provided with a wall or surface 16 that is molded or cast to conform to the mesial surface 17 of the abutment tooth 11. Hence, the wall 16 is not only curved in horizontal cross-section generally to conform to the shape of the mesial surface of tooth 11 with which the surface 16 contacts, but it is inclined from the vertical reciprocally with respect to the undercut mesial surface of tooth 11. In Fig. 6 the relation of the surface 16 of the section A to the mesial undercut surface 17 of tooth 11 is clearly indicated.

The pillar 15 is provided with a rearwardly, that is, distally, directed lug 18 adapted to seat in a recess that may be ground, if necessary, in the occlusal surface of the tooth 11 as indicated at 19 in Fig. 6. The forward or mesial surface 20 of the pillar 15 is disposed in a plane that will accommodate insertion of the section B in a direction parallel to the median line of the undercut distal surface 21 of the abutment tooth 10 as will be more fully described hereinafter. That is, the lines X and Y, which represent the median lines of the surfaces 20 and 21 respectively, should be either parallel or upwardly convergent as viewed in Fig. 6. Hence, when the section A of the improved denture has been placed in position in the edentulous space, the two surfaces 20 and 21, having their median lines parallel or convergent in the direction of the roots of the teeth, will accommodate insertion of the section B.

Again, referring to Fig. 6 it will be seen that the sections A and B carry, respectively, the artificial teeth C and 22 which replace the natural teeth above-mentioned. As stated, the plate of section A, as shown in Fig. 5, has its gum contacting surface 12 shaped in conformity with the contour of the portion of the gum ridge over which it is to seat; and section B is provided with a similar gum contacting surface 24. The mesial surface 25 of the section B is inclined comple-

mentarily with respect to the undercut distal surface 21 of the tooth 10 and transversely corresponds to the transverse curvature or contour of the tooth while the distal end of section B has a surface 26 that is inclined for contact with the surface 20 of section A. The mesial end portion of the section B, as shown, also is provided with a lug 27, that extends mesially onto a seat 28, ground if necessary, in an occlusal surface of the 10 abutment tooth 10 as indicated in Fig. 4.

The artificial teeth C and 22 are secured to the sections A and B by any approved means, such as by pins or studs 29 formed integrally with the respective section in the casting or molding thereof and which enter bores or recesses 30 provided in the teeth. Cement maintains the teeth in proper relation.

The two surfaces 12 and 24 respectively of sections A and B provide substantially a continuous 20 ridge-contacting and ridge-conforming surface when the sections are assembled within the edentulous space.

As will be apparent from the foregoing, the sections A and B are moulded or cast to fit the 25 edentulous area of a particular patient and hence all sections A and B of the improvements will not be of the precise shape shown in the drawings nor will the angles and cross sectional shapes of the distal and mesial surfaces of the denture 30 be precisely as illustrated. The distal and mesial surfaces of the abutment teeth however, or at least one of such surfaces, must be of an undercut form for taking full advantage of the present improvements.

35 In placing the sections A and B into operative position, the section A is first placed in the edentulous space with the lug 18 upon the seat 28 and with the wall 16 contacting the mesial wall 17 of the tooth 11.

40 The section B is next placed in position and may be moved into proper position in a direction parallel to the medial line of either surface 20 or 21 since, as above described, these surfaces are disposed at angles to permit such movement. In pressing the section B into position, the wedging action of wall 20 on wall 26 tends to urge the sections longitudinally in opposite directions and thereby effect close inter-engagement of the surfaces 16-17 and 21-25, respectively, the lug 27 of section B being positioned upon its seat 28.

As best shown in Fig. 6, the key-tooth C, when cemented in place, is in line to block vertical displacement of the section B, by engagement with the surface 31 thereon; and, because section B 55 overlies section A at surfaces 20-26, section B is in line to block vertical displacement of section A. Thus, with C cemented in place, none of the parts are individually displaceable. Furthermore, due to the reciprocal relation between 60 surfaces 16-17 and 21-25, both of the surfaces 17 and 21 being undercut, the assembled denture is not displaceable as a unit out of the edentulous space.

The lugs 18 and 27 receive the gum-wise thrust 65 of the teeth C and 22 in biting or chewing and thus relieve the gum ridges from excessive pressure. The lugs also restrain rocking movement of the denture with respect to the ridge of the gums as an axis, and cooperate with the arcuate, 70 gum fitting lower surfaces 12 and 24 of the sections A and B, as well as with the arcuate shape of the mesial and distal surfaces of the denture (which closely contact the respective surfaces of the abutment teeth), in inhibiting lateral displacement of the denture, that is lingually or bucc-

cally. The movement of the denture in an axial direction, that is, away from the gum surface on which the denture fits, is restrained by the coaction of the end walls 16 and 25 of the sections A and B with the respective contacting undercut walls of the abutment teeth.

Fig. 8 illustrates the adaption of the structure shown in Figs. 1 to 7 inclusive to an edentulous area having but one undercut tooth surface, indicated at 17'. The opposite end of the surface is defined by an abutment tooth 10' having a vertical surface 36. The denture shown in Fig. 8 is in all respects similar to the denture above described except as modified for coaction with the tooth indicated as 10' which has a vertical rather than an undercut surface. The cooperating surface 37 of the section A' conforms to the surface 36. Assuming the parts are assembled as described in connection with the form shown in Figs. 1 to 7, that is by inserting A', B' and C', in that order, and cementing C' in place, the denture of Fig. 8 will not move vertically by gravity (assuming it is an upper denture) since any vertical movement would cause the undercut surface 17' of tooth 11' to effect a wedging action on the complementary surface 18' of section B', the component of which would tend to force the denture to the right as viewed in Fig. 8. Such movement, however, is resisted by the abutment tooth 10'. Likewise, the right-hand end of the denture shown in Fig. 7 cannot swing downwardly about the lug 18' of section B' as a pivot for the reason that no clearance for such arcuate movement is present within the edentulous area.

It will be seen that one or both of the denture sections may be provided with more than one tooth where the edentulous area requires a greater number of teeth than that shown, or with a single tooth in one and no tooth in the other. It will also be apparent that the improved denture, having the two sections A and B arranged in end-to-end relation, is retained as a unit against vertical displacement by reason of the action between the respective contiguous surfaces of the abutment teeth and the remote ends of the denture sections which are reciprocally or complementarily shaped to conform to or mate with the respective surfaces of the teeth. It will also be apparent that slight movement of the sections A and B in axial directions may occur as section B is pressed into firm position in the edentulous space due to the coaction of the reciprocally shaped inclined faces 23 and 26 which tends to move the sections in opposite directions against the respective teeth 10 and 11. The close-fitting relationship of the remote end portions of the denture and the abutment teeth avoids the formation of food traps or cavities between the abutment teeth and the adjacent artificial teeth since the respective inter-proximal spaces are closed by the adjacent portions of the denture sections A and B. Likewise, since the inclined surfaces 23 and 26 are reciprocally formed, they closely interfit and exclude food particles from between the same and since they are retained in such interfitting relation by the blocking action of the key-tooth they, in turn, retain the remote ends of the sections in close contact with the abutment teeth.

Another form of the invention, applicable particularly to anteriorly positioned dentures, such as incisors, is illustrated in Figs. 9 to 16 inclusive and will now be described. A problem in applying the previously described embodiment to the replacement of incisors arises because those teeth

do not have concave occlusal surfaces for the retention of lugs such as 18 and 27 to restrain the denture against rocking movement about the gum ridge as an axis.

In Figs. 9 to 16, a set of natural upper teeth is again shown, two of which have been replaced by a denture illustrative of the present invention. The two natural teeth that have been removed are the first and second incisors on the right side. Hence, the abutment teeth for the edentulous area caused by the removal of the two natural teeth are the first left incisor 110 and the third right incisor 111. As indicated in Fig. 11, the mesial surfaces of teeth 110 and 111 are undercut surfaces, that is, each converges generally toward the root tip of the respective tooth in the manner previously described.

The denture illustrated in Figs. 9 to 16 comprises three coacting parts, namely, sections D and E which are insertable in the edentulous area in the order named and the key-tooth F which is securable to D, as by cementing, to hold the assembled denture securely in place. It will be apparent, as the description proceeds, that parts D, E and F are, respectively, equivalents of parts A, B and C of the previously described embodiment. Fig. 16 illustrates the parts D, E and F as viewed lingually, somewhat from the left in Fig. 9, and also shows the parts in inverted relation, Fig. 9 being a view of the upper set of teeth. The section D is a casting of metal or a molding of appropriate plastics material and comprises a surface 112 saddle-shaped in accordance with the gum surface or ridge portion over which it is to be worn, as indicated in Fig. 12. The body portion 113 of the section D has formed thereon a wall or surface 116 that is molded or cast to conform to the mesial surface 117 of the abutment tooth 111. Hence, the wall 116 is not only curved in horizontal cross-section generally to conform to the shape of the mesial surface of tooth 111 with which the tooth contacts, but it is inclined from the vertical reciprocally with respect to the undercut mesial surface of tooth 111. In Fig. 11, the relation of the surfaces 116 and 117 is clearly indicated.

The body 113 of section D is provided with a sideways, that is distally directed lug 118 adapted to seat on the lingual face of the abutment tooth 111 as indicated in Fig. 15. The opposite or mesial surface 120 of the section D is disposed in a plane that will accommodate insertion of the section E in a direction parallel to the median line of the undercut mesial surface 121 of the abutment tooth 110 as will be more fully described hereinafter. That is, the lines W and Z, which represent the median lines of the surfaces 120 and 121, respectively, should be either parallel or upwardly divergent as viewed in Fig. 15. Hence, when the section D of this embodiment has been placed in position in the edentulous space, the two surfaces 120 and 121, having their median lines parallel or convergent in the direction of the roots of the teeth, will accommodate insertion of the section E.

Referring to Fig. 15 it will be seen that the sections D and E carry respectively the artificial teeth F and 122 which replace the natural teeth above mentioned. As stated, the saddle of section D, as shown in Fig. 12, has its gum contacting surface 112 shaped in conformity with the contour of the portion of the gum ridge upon which it is to seat; and section E is provided with a similar gum contacting surface 124, as indicated in Fig. 13. The mesial surface 125 of the

section E is inclined complementarily with respect to the undercut mesial surface 121 of the tooth 110 and transversely corresponds to the transverse curvature or contour of the tooth while the distal end of section E has a surface 123 that is inclined for contact with the mesial surface 120 of section D. The mesial end portion of the section E is also provided with a lug 127 that extends distally onto the lingual surface of abutment tooth 110. The two lugs 118 and 127 thus bear on the inside surface of the abutment teeth to prevent outward displacement of the denture, as well as to transmit biting load to the abutment teeth thereby relieving the gum ridge of the greater proportion of either of such loads.

The section E is provided with an extension 41 which preferably will be molded or cast integral therewith and so formed as to lie flat against the palate to avoid a food trapping space therebetween. The extension 41 terminates in an anchor lug 42 (Fig. 14) which is seated onto an occlusal seat 43 between a pair of teeth remote from the edentulous space, the anchor seat in this case being between the first and second bicuspids 44 and 45, respectively. The anchored extension 41 is effective to prevent the inward or lingual displacement of the denture and thus complements the function of the lugs 118 and 127 which prevent outward displacement as above described.

The artificial teeth F and 122 are secured to the sections D and E respectively by any approved means such as by pins or studs 129 formed integrally with the respective section in the casting or molding thereof, lying substantially parallel to the anterior surfaces of the sections, and which enter bores or recesses 130 provided in the teeth. Cement maintains the teeth in proper relation. As best shown in Figs. 12, 13 and 15, the artificial tooth F is formed with a lingually extending ledge 46 which overlies the edge 47 of section E thereby preventing parallel displacement of the latter when the tooth F is cemented in place.

The two surfaces 112 and 124, respectively, of sections D and E provide substantially a continuous ridge-contacting and ridge-conforming surface when the sections are assembled within the edentulous space.

As will be apparent from the foregoing, the sections D and E are molded or cast to fit the edentulous area of a particular patient and hence sections D and E of the improvements will not be of the precise shape shown in the drawings nor will the angles and cross-sectional shapes of the distal and mesial surfaces of the denture be precisely as illustrated. The mesial surfaces of the abutment teeth, however, or at least one of such surfaces, must be of a natural or ground undercut form for taking full advantage of the present improvements.

In placing the sections D and E into operative position the section D is first placed in the edentulous space with the lug 118 seated upon the lingual surface of abutment tooth 111 and with the wall 116 contacting the mesial wall 117 of the tooth 111. The section E is next emplaced and may be moved to the proper position in a direction parallel to the medial line of either surface 120 or 121 since, as above described, these surfaces are disposed at angles to permit such movement. In placing the section E into position the wedging action of wall 120 on wall 126 tends to urge the sections longitudinally in opposite directions and thereby effect close inter-

engagement of the surfaces 116-117 and 121-125 respectively, the lug 127 of section E being seated upon the lingual face of abutment tooth 110.

5 As best shown in Fig. 15, the key-tooth F, when cemented in place, is in line to block vertical displacement of the section E by interengagement of surfaces 46 and 47; and, because section E overlies section D at surfaces 120-126, section

10 E is in line to block vertical displacement of section D. Thus, with F cemented in place, none of the parts of the denture is displaceable out of the edentulous area, individually. Furthermore, due to the reciprocal relation between the surfaces 116-117 and 121-125, both of the surfaces 117 and 121 being undercut in this particular example, the denture is not displaceable out of the edentulous space, as a unit.

The lugs 118 and 127 receive the gum-wise 20 thrust of the teeth F and 122 in biting or chewing and thus relieve the gum ridges from excessive pressure. The lugs also restrain anterior, that is forwardly outward, rocking movement of the denture with respect to the ridge of the gum as an axis. The extension 41, anchored as described between the bicuspids 44 and 45, cooperate with the arcuate gum-fitting lower surfaces 112 and 124 of the sections D and E, as well as with the arcuate shape of the mesial and distal surface

30 of the denture (which closely contact the respective surfaces of the abutment teeth) in inhibiting lateral displacement of the denture in the inward or lingual direction. The movement of the denture in a vertical direction, that is, away from

35 the gum surface on which the denture fits, is restrained by the co-action of the end walls 116 and 125 of the sections D and E with the respective contacting undercut walls of the abutment teeth. As described in connection with the em-

40 bodiment of Fig. 8, the embodiment of Figs. 9 to 16 is likewise usable with an edentulous space having only one undercut abutment tooth.

Furthermore, as also described in connection with the previous embodiments, it will be apparent 45 that one or both of the denture sections D and E may be provided with more than one tooth where the edentulous area requires a greater number of teeth than that shown, or with a single tooth in one section and no tooth in the other.

50 From the foregoing description, it will be seen that the embodiment of Figs. 9 to 16 is basically the same as that previously described for the other embodiments, with the lugs 118 and 127 being applied to the lingual rather than the occlusal surfaces of the abutment teeth, and with the anchored extension 41 effective to inhibit the inward displacement of the denture. Otherwise the basic structure is the same and provides the 55 same advantages of avoiding the formation of food traps and eliminates the use of clips and bars and the like, as mentioned in connection with the first described embodiments.

While I have shown and described dentures that are illustrative of the invention, various changes 60 in the details shown may be made within the spirit of the invention as covered by the appended claims.

I claim:

1. A denture for use in an edentulous space 70 defined by undercut walls of two abutment teeth comprising a pair of denture sections adapted to be positioned consecutively in said space and each provided with remote end walls reciprocally shaped with respect to and adapted to contact the undercut surfaces of the respective teeth,

said sections being provided with interfitting adjacent end walls reciprocally shaped to urge the sections in opposite directions as the second of said sections is pressed into interfitting relation with the first section within said space for thereby urging said remote end walls into contact with the said surfaces of the respective teeth for restraining vertical movement of the denture from said space, and a keying member comprising an artificial tooth mounted on said denture effective to maintain said sections in position in said edentulous space.

2. A denture for use in an edentulous space defined by undercut walls of two abutment teeth comprising a pair of denture sections adapted to be positioned consecutively in said space and each provided with remote end walls reciprocally shaped with respect to and adapted to contact the undercut surfaces of the respective teeth, said sections being provided with interfitting adjacent end walls reciprocally shaped to urge the sections in opposite directions as the second of said sections is pressed into interfitting relation with the first section within said space for thereby urging said remote end walls into contact with the said surfaces of the respective teeth for restraining vertical movement of the denture from said space, and a tooth carried by said denture effective to retain the adjacent ends of said sections in said interfitting relation.

3. A denture for use in an edentulous space defined by undercut walls of two abutment teeth comprising a pair of denture sections adapted to be positioned consecutively in said space in end-to-end relation, the remote ends of said sections being shaped reciprocally with respect to the respective undercut walls, the adjacent ends of said sections being reciprocally shaped for interfitting contact upon the positioning of said sections in said space with said remote ends in contact with said walls, and means including an artificial tooth for securing said adjacent ends of the sections in interfitting contact and retaining said remote ends in contact with said walls and thereby restraining vertical displacement of the denture from said space.

4. A denture for use in an edentulous space defined by undercut walls of two abutment teeth comprising a pair of denture sections adapted to be inserted consecutively in said space, the first insertable section having a tooth contacting end wall reciprocally shaped for contact with the undercut wall of one of said teeth and having an opposite end portion disposed at an angle at least as great as the angle of the undercut portion of the other abutment tooth, said second insertable section having an end wall shaped reciprocally with respect to the undercut wall of the latter tooth for contacting the same and having an opposite end wall portion disposed in a plane parallel to the plane of the second mentioned end portion of the first section and adapted to contact the same when the sections are in position in said space, and means for retaining said last mentioned end portions of the sections in contact for retaining the said tooth-contacting ends of the respective sections in engagement with the undercut walls of the respective abutment teeth, said means including an artificial tooth carried by said first insertable section in a position with respect to said second insertable section to retain the latter in position within said edentulous space.

5. A denture for use in an edentulous space defined by undercut walls of two abutment teeth

comprising a pair of separable sections insertable consecutively in end-to-end relation in said space, the first insertable section having an end wall reciprocally shaped for contact with the undercut wall of one of said teeth, the second insertable section having an end wall shaped reciprocally for contact with the undercut wall of the second tooth, the other ends of the sections having cooperating portions adapted for mutual contact when the sections are in position in said space and being arranged in planes enabling said second section to be inserted in said space in a vertical direction paralleling the plane of the undercut wall of said second tooth, and an artificial tooth secured to said second insertable section in position to key said first insertable section in place within the edentulous space.

6. A denture for use in an edentulous space defined by undercut walls of two abutment teeth comprising a pair of separable sections insertable consecutively in end-to-end relation in said space, the first insertable section having an end wall reciprocally shaped for contact with the undercut wall of one of said teeth, the second insertable section having an end wall shaped reciprocally for contact with the undercut wall of the second tooth, the other ends of the sections having cooperating portions adapted for mutual contact when the sections are in position in said space and being arranged in planes enabling said second section to be inserted in the space in a vertical direction paralleling the plane of the undercut wall of said second tooth and enabling said second section to restrain the first section from vertical displacement from its position in said space, and a tooth securable to said first section after the second section is in place in a position to block vertical displacement of the second section from its position in said space.

7. A denture for use in an edentulous space defined by undercut walls of two abutment teeth comprising a pair of separable sections insertable consecutively in end-to-end relation in said space, the first insertable section having an end wall reciprocally shaped for contact with the undercut wall of one of said teeth, the second insertable section having an end wall shaped reciprocally for contact with the undercut wall of the second tooth, the other ends of the sections having cooperating portions adapted for mutual contact when the sections are in position in said space and being arranged in planes enabling said second section to be inserted in the space in a vertical direction paralleling the plane of the undercut wall of said second tooth, and a keying member for holding said denture in said space comprising an artificial tooth securable onto one of said sections after both are in place in a position with respect to the other section to prevent vertical displacement of the latter from said space.

8. A denture for use in an edentulous space defined by walls of two abutment teeth comprising a pair of separable sections insertable consecutively in end-to-end relation in said space, at least one of said walls being undercut, the first insertable section having an end wall reciprocally shaped for contact with said wall of one of said teeth, the second insertable section having an end wall shaped reciprocally for contact with said wall of the second tooth, the adjacent ends of the sections having cooperating portions adapted for mutual contact when the sections are in position in said space and being arranged in planes enabling said second section to be inserted in the space in a vertical direction paralleling the plane

of said wall of said second tooth, and means for retaining said adjacent end portions of the sections in close mutual contact to maintain the denture in said space, said means including an overlapping of one of said sections with respect to the other at their adjacent end portions whereby said one section is effective to restrain the other section from vertical displacement out of the edentulous space, said means also including an artificial tooth secured to said other section a portion of which is positioned to block vertical displacement of said one section.

9. A denture for use in an edentulous space defined by walls of two abutment teeth, at least one of said walls being undercut, comprising a pair of denture sections adapted to be positioned consecutively in said space and each provided with remote end walls reciprocally shaped with respect to and adapted to contact said walls of the abutment teeth, said sections being provided with interfitting adjacent end walls shaped reciprocally with respect to one another and with said adjacent wall of one of said sections overlying the other to restrain the latter from vertical displacement, said one section having an extension anchored on a tooth other than the abutment teeth.

10. A denture for use in an anterior edentulous space defined by walls of two abutment teeth, at least one of said walls being undercut, comprising a pair of denture sections adapted to be positioned consecutively in said space and each provided with remote end walls reciprocally shaped with respect to and adapted to contact said walls of the abutment teeth, said sections being provided with interfitting adjacent end walls shaped reciprocally with respect to one another, one of said adjacent walls overlying the other to restrain the section carrying the latter from vertical displacement, said one section having an extension anchored on a posterior tooth remote from said abutment teeth.

11. A denture for use in an edentulous space defined by walls of two abutment teeth, at least one of said walls being undercut, comprising a pair of denture sections adapted to be positioned consecutively in said space and each provided with remote end walls reciprocally shaped with respect to and adapted to contact said walls of the abutment teeth, said sections being provided with interfitting adjacent end walls shaped reciprocally with respect to one another and having said adjacent wall of one of said sections overlying the other to restrain the latter from vertical displacement out of said space, said one section having an extension anchored on a tooth remote from said abutment teeth, said denture having a keying member comprising an artificial tooth securable thereto and having a gum-facing shoulder engageable with said one section to restrain it from vertical displacement out of said space.

12. A denture for use in an anterior edentulous space defined by wall of two abutment teeth, at least one of said walls being undercut, comprising a pair of denture sections adapted to be positioned consecutively in said space and each pro-

vided with remote end walls reciprocally shaped with respect to and adapted to contact said walls of the abutment teeth, said sections being provided with interfitting adjacent end walls shaped reciprocally with respect to one another and having the adjacent wall of one of said sections overlying the other to restrain the latter from vertical displacement, one of said sections having an extension anchored in a posterior position remote from said abutment teeth and effective to restrain inward or lingual displacement of said denture, and said denture having at least one portion engageable with a lingual surface of one of the abutment teeth to restrain outward or anterior displacement of the denture.

13. A denture for use in an edentulous space defined by walls of two abutment teeth, at least one of said walls being undercut, comprising a pair of denture sections adapted to be positioned consecutively in said space and each provided with remote end walls reciprocally shaped with respect to and adapted to contact the said walls of the abutment teeth, each of said sections also having an extension engageable with one of said abutment teeth whereby biting or tilting loads applied to said denture will be transmitted to said abutment teeth, said sections being provided with interfitting reciprocally shaped adjacent end walls, one of said sections having a keying tooth securable thereto after both sections are assembled within said space and having a portion overlying the other section whereby it is effective to maintain both of said sections in assembled positions within said edentulous space.

14. A denture for use in an edentulous space defined by walls of two abutment teeth, at least one of said walls being undercut, comprising a pair of denture sections adapted to be positioned consecutively in said space and each provided with remote end walls reciprocally shaped with respect to and adapted to contact the said walls of the abutment teeth, each of said sections also having an extension adapted to fit into a groove in an occlusal surface of one of said abutment teeth to transmit load applied to said denture to said abutment teeth, said sections being provided with interfitting reciprocally shaped adjacent end walls one of which is shaped to overlie the other, one of said sections having a keying tooth attachable thereto after both sections are in position within said space and engageable with both sections whereby it is effective to maintain both of said sections in assembled positions within said edentulous space.

55 JAMES J. MANIOLA.
Administrator of the Estate of Robert J. Maniola,
Deceased.
